ERNEST LOUIS VICTOR RÉBILLON, OF MONTESSON, AND RENÉ ADAM, OF PARIS,
FRANCE.

MOTION-PICTURE PROJECTING APPARATUS.

Application filed October 22, 1923, Serial No. 670,098, and in France December 30, 1922.

Up to now, in the majority of motion picture projectors used, the reels, one of which receives the film before its passage into the projector, while the other receives the film 5 after its passage through the said projector, are arranged in one and the same plane; the film, in coming from the feeding reel, passing directly through the apparatus and being wound on the receiving reel generally 10 arranged below.

This invention relates to a projector in which the feeding and receiving rolls are done away with and replaced by simple cores without sides or flanges, one of which 15 is arranged against the right hand wall of the casing of the apparatus, and the other against the left hand wall of the casing, all the other parts being enclosed in the said casing.

20 The film coming from the feeding core, forms a natural enlarged loop in order to pass into the apparatus and to be wound on the receiving core.

This arrangement of the two feeding and 25 receiving cores relatively to the casing containing all the parts of the projector, with the formation of a continuous enlarged loop between the two cores, constitutes one of the characteristic features of the invention.

30 As will be seen by examining the following description, the invention is characterized at the same time by other important points which will be better understood with reference to the accompanying drawings in 35 which

Figure 1 is a side elevation of the apparatus shown in front elevation in Figure 2.

Figure 3 is a second side elevation showing the opposite side to that in Figure 1.

40 Figure 4 shows the apparatus on an enlarged scale in vertical longitudinal section.

Figure 5 is a vertical cross-section of the same.

Finally, Figures 6 and 7 are detail views 45 of the claw holder enabling the film to be advanced by jerks or intermittently.

As will be seen from the drawings, all the active parts of the apparatus other than the receiving and feeding cores and the 50 driving rollers, are enclosed in a casing *a* which can be mounted by means of any suitable pivoted joint *b* on a supporting leg *c* for the purpose of enabling it to assume

easily and instantaneously any suitable position. 55

At one of the sides of the casing is the feeding core *d* on which is wound the film before its passage through the apparatus. It is a simple core of wood or other material, without any flanges or sides, and it is 60 the wall of the casing *a* that constitutes at one side the side cover or flange of the core.

At the other side, no flange or side cover is required because of the direction of the pull exercised on the film. Nevertheless, 65 by way of precaution, a finger *d'* holding the film in place could be mounted on the spindle of the core.

At *e* is arranged a driving roller or drum which, by means of the driving gear described further on, unwinds the film from 70 the feeding core.

The film *f* thereupon forms an upper loop and then descends through the apparatus. It comes out at the bottom portion 75 of the apparatus, and after having formed a bottom loop, is exposed to the action of a second driving roller or drum *e'* in order to be finally wound on the core *d''* similar to the core *d* and, if necessary, comprising, 80 like the core *d*, a holding finger *d'*. In these conditions, the film tends to take a perfectly natural or normal path which moreover it follows owing to its inclination to become wound upon itself. 85

All the inner parts of the apparatus, shown in Figures 4-7, will be now examined in detail: these parts make possible the intermittent movement of the film in the 90 interior of the casing.

At *g*, in the centre of the casing, is mounted a shaft which can be rotated by hand, by means of a handle *g'*, and in such event the said shaft is provided with a fly wheel *g''* for the purpose of regularizing the 95 movements of the handle.

It will be understood that in place of the fly-wheel *g''* could be mounted an electric motor to which current would be supplied at *h* in the bed of the apparatus. In that 100 case, the motor, instead of driving by means of a reducing gear the shaft *g*, could drive a second shaft *i*, the object of which will be seen later on.

The shaft *g* is provided at *j* with a helical pinion engaging with a pinion *j'* keyed 105

to the cross shaft j'' . This cross-shaft j'' is provided at each end with a pulley k .

Over each of the said pulleys k passes a chain or cable k' winding on a loose pulley k'' mounted on a stationary shaft l .

The pulleys k are controlled by pawls carried by the two driving rollers or drums e, e' which are also seen in Figures 1 and 3. Owing to the combination of each pulley k 10 with its corresponding driving roller, a free wheel device is obtained.

The shaft g is moreover provided at its front portion with another toothed wheel m engaging with a pinion m' keyed to the shaft 15 section i , which section, as already stated, could be extended rearwards for the purpose of being driven by the electric motor if necessary.

The said shaft i is provided at o with the 20 rotating shutter enabling the light to be shut off at the moment of moving the film, as in any projection apparatus.

The said shutter is provided with a triangular cam o' (Figure 6) which, during 25 the rotation of the shaft i , and therefore of the shutter o , produces the rising and descending movements of a frame p .

To the said frame p is secured a spring blade q carrying the claws r . This blade 30 is bent at the top at r' in order to receive the action of a boss s secured to the shutter o .

When the bent portion r' is opposite the highest portion of the boss s , the claws r are 35 pushed to the right (Figure 7) and engage with the holes of the film, thus enabling the film to be driven downwards by the movement of the frame p .

On the contrary, when the bent portion r' is on the less projecting portions of the boss 40 s , the claws are disengaged from the film, and the frame p can be moved without driving the film.

The lighting can be done by means of an 45 incandescent lamp u mounted in a holder u' hinged at v to the top of the apparatus, owing to which the lamp can be withdrawn from the apparatus by turning the holder u' , so as to examine the said lamp and replace it if necessary.

50 It will be understood that the apparatus can be worked without any inconvenience in one or in the other direction, the film being moved downwards or upwards at will.

Moreover, the film can be stopped instantaneously at any point of the projection. It 55 will be understood how important this arrangement would be for the use of cinematographs for educational purposes, as the professor could leave the apparatus standing still in order to explain at greater length a view of the film, or turn back the film, if

his lesson requires him to refer again to a view already projected.

In the preceding description, no stress has been laid on certain detail parts which are 65 obvious, such as for instance: the joint b which can be of any desired suitable type, the brake shoes or blocks x controlled by springs x' pressing the film against the driving rollers e, e' , the object glass y etc.; these 70 are, in fact, arrangements which do not offer any novel features and do not come within the invention.

We claim as our invention:—

1. Motion picture projecting apparatus, 75 comprising a casing; a feeding reel and a receiving reel for the film mounted externally of the casing at opposite sides thereof, each reel consisting of a cylindrical core which is disposed in close proximity to the adjacent side wall of the casing so that such wall serves as a flange at the inner side of the core to prevent displacement of the film from the core in an inward direction; driving rollers mounted at opposite sides of the 80 casing for engagement with the film; and mechanism within the casing for driving said rollers.

2. Motion picture projecting apparatus, 85 comprising a casing; an objective connected thereto; a feeding reel and a receiving reel for the film mounted externally of the casing at opposite sides thereof; a pair of driving rollers mounted at opposite sides of the 90 casing for engagement with the film and so arranged that the film travels from the feeding reel over the roller on the same side of the casing, then forms an enlarged depending loop, then travels upwardly in a substantially straight line past the inner end of the objective, then forms an enlarged upwardly-directed loop, and then passes around and beneath the roller on the other side of the casing and travels therefrom to the receiving reel; and mechanism within the 95 casing for driving said rollers.

3. Motion picture apparatus, comprising a casing; a cross-shaft mounted in the casing and projecting beyond its opposite side walls; a feeding reel and a receiving reel for the film mounted externally of the casing at opposite sides thereof; mechanism within the casing for rotating the cross-shaft; a driving roller loosely mounted on each projecting end of said shaft for engagement 100 with the film; and a pair of pulleys on said shaft having pawls to engage and rotate said rollers.

In testimony whereof we have signed this specification.

RENÉ ADAM ERNEST LOUIS VICTOR RÉBILLON.
